UNITED STATES PATENT OFFICE.

WILLIAM W. JACQUES, OF NEWTON, MASSACHUSETTS, ASSIGNOR TO THE EDISON PHONOGRAPH TOY MANUFACTURING COMPANY, OF MAINE.

PHONOGRAPH-DOLL.

SPECIFICATION forming part of Letters Patent No. 400,851, dated April 2, 1889.

Application filed November 30, 1888. Serial No. 292,249. (No model.)

To all whom it may concern:

Be it known that I, WILLIAM W. JACQUES, of Newton, in the county of Middlesex and State of Massachusetts, have invented certain improvements in Phonograph-Dolls, of which the following is a specification.

My present invention relates to certain improvements in phonograph-dolls, and will be more readily understood by reference to a patent issued to me, dated May 22, 1888, for combined doll and phonograph, No. 383,299.

In the above-mentioned patent I have shown and described a resonating tube or chamber connecting the diaphragm of the phonograph with an opening in the top of the doll's head, for the purpose of conducting the sound from the diaphragm of the phonograph to the outside of the doll, and also for the purpose of selecting and re-enforcing the talking emitted by the diaphragm, to the exclusion of other sounds. I find by further experiment that I may advantageously remove this resonant tube and utilize the air-space inclosed within the body of the doll, provided it is in free communication with the diaphragm of the phonograph, as a resonating-chamber to select and re-enforce the talking emitted by the diaphragm; and I find, moreover, that I may do away with the orifice for the emissions of sound, provided the head or body composing the walls of such resonating-cavity be made of material easily set in vibration, like papier-maché, thin metal, thin wood, thin bisque, or, in fact, such materials as the heads and shoulders of dolls are most usually made of. I get excellent results by mounting the phonograph inside a doll's body made of papier-maché or tin, and completing the doll by a hollow head of papier-maché or bisque, the cavity within the body and head acting as a resonator to clarify and re-enforce the talking emitted by the diaphragm, and the walls of these materials readily allowing these clarified and reinforced vibrations to be communicated to the outside air.

In the accompanying drawings, Figure 1 is a sectional view of the body of a doll containing a phonograph and having a hollow head to serve as a resonating-chamber. Fig.

2 is a similar view with my improved globular resonator attached to the phonograph, in which—

g is the diaphragm forced into vibration by means of the phonograph-record in the manner described in my previous patent above referred to, and *c c* indicate the resonating-cavity in free communication with said diaphragm, and *d d* indicate the head and body of the doll forming the walls of said cavity.

When I wish to make the talking of the dolls particularly loud and clear, I attach to the phonograph a further resonator of the form shown in Fig. 2 of the accompanying drawings. This consists of a hollow globe, *b*, open at the top, so that its cavity is in free communication with the cavity *c c*. This globe is divided into two parts, of unequal size and different shape, by the conical-shaped partition *u*, which partition is perforated at *o*. The globe opens at the bottom into an annular cavity, *e*, the walls of this cavity inclosing the diaphragm *g* on its upper side.

The form both of the resonator and the partition which divides it (shown in Fig. 2 and above described) is the best I have yet discovered, though they may be considerably varied without great detriment to its efficiency. The essential features are a globular resonator open at the top, divided into two parts of unequal size and different shape by a perforated diaphragm, and communicating at the bottom with an annular space inclosing the upper side of the diaphragm. I prefer to make the resonator of zinc, as this gives a good quality to the sounds emitted by the diaphragm; but I may make it of wood, papier-maché, or other resonant material. This resonator, of course, may be used with a doll having either a closed or a perforated body, or may be used on a phonograph without any inclosing doll's body; but the series of cavities *e*, *a*, *b*, and *c* give the most pleasing quality of tone to the talking emitted by the diaphragm that I have yet obtained.

In view of the above-described improvements, I claim—

1. The combination of a phonograph and a doll provided with a body containing and

carrying said phonograph, and a closed hollow space in communication with the diaphragm and within the doll.

2. The combination of a phonograph and a doll provided with a body carrying said phonograph, and a closed hollow head to act as a resonator.

3. The combination, within the body of a doll, of a phonograph supported thereby, and a globular resonating-chamber divided into

two portions by a perforated conical partition, substantially as described.

In testimony whereof I have signed my name to this specification, in the presence of two subscribing witnesses; this 27th day of 15 November, 1888.

WILLIAM W. JACQUES.
